T. M. AVERY

SIFTPROOF BAG

Filed June 26, 1925

UNITED STATES PATENT OFFICE.

TRUE M. AVERY, OF HUDSON FALLS, NEW YORK, ASSIGNOR TO UNION BAG & PAPER CORPORATION, OF HUDSON FALLS, NEW YORK, A CORPORATION OF NEW JERSEY.

SIFT-PROOF BAG.

Application filed June 26, 1925. Serial No. 39,824.

The present invention relates to improvements in paper bags of the square-bottom type which have pleats or tucks in the opposite edges thereof, and the object of the invention is to provide a novel and improved bag of this type which shall have a sift-proof bottom.

Bags of this type have generally been made by feeding a flat strip of paper to a former and bending or folding the longitudinal edges of the strip over the former to produce a tube, cut-off mechanism acting to sever the tube into bag sections of appropriate length, after which an end of each bag section is pasted and folded against a side of the bag to form the closure for the bottom thereof. Heretofore, it has been customary, in manufacturing bags of this type, to make the side of the bag on which the longitudinal seam is formed and against which the bottom fold is pasted, somewhat narrower than the opposite or face side, but it has been found that in so doing, the corners of the bottom fold which were wider than the seam side of the bag projected laterally beyond the longitudinal edges thereof, so that while the remainder of the bottom fold was pasted to the seam side of the bag there was no backing or support against which the corners of the fold could be pasted, in consequence of which said corners of the bottom fold remained unpasted and unsecured, and left crevices through which powdery or granular material placed in the bag would sift out, thus causing a loss in the contents of the bag and being otherwise objectionable.

The present invention produces a sift-proof bag thus overcoming the objections found to exist respecting bags of this type as heretofore manufactured. According to the present invention, the seam side of the bag, against which the bottom fold is pasted, is made wider than the opposite side or face thereof, thus providing a backing or support of a width at least equal to the full width of the bottom fold, and the corners of the bottom fold, as well as the remainder thereof, are pasted against the marginal portions of the backing or support thus provided, thereby producing a closure of the bottom fold throughout its width, including its corners, which renders the bag sift-proof.

In the accompanying drawing:—

55 Figure 1 is a view of the rear of a square-

bottom bag made in accordance with the present invention, one corner on the bottom fold being shown by the full lines as turned back and by the dotted lines in pasted position.

60

Figure 2 represents a longitudinal section through the bag taken on the line 2—2 of Figure 1.

Figure 3 is a detail perspective view of one of the lower corners of the bag made as shown in Figures 1 and 2, this figure illustrating the manner in which one of the corners of the bottom fold is pasted to the seamed side or rear face of the bag.

Figure 4 is a view of one end of a bag section prior to the bending of the bottom fold.

Similar parts are designated by the same reference characters in the different views.

The present invention is applicable generally to paper bags of the well-known square-bottom type, such bags usually having pleats or tucks in their opposite longitudinal edges and the bottom of the bag being closed and secured by a bottom fold which is pasted against a side of the bag. One embodiment of the invention is shown in the accompanying drawing and will be hereinafter described in detail, but it is to be understood that equivalent bag structures are contemplated and such will be included within the scope of the claims.

In the present instance, 1 designates the face side and 2 designates the seam side of a square-bottom bag, 3 designating the seam, and 4 designates the pleats or tucks which are formed in the longitudinal edges of the bag, the bag being of a well-known type which is usually manufactured by feeding a strip of paper to a former and folding the longitudinal edges of the strip around the former to produce a paper tube from which the bag sections may be cut. The pleats or tucks 4 are formed in the longitudinal edges of the paper tube as the same is made on the former. A cut-off device, the construction and operation of which are well-known in the art, serves to sever the paper tube into appropriate lengths to serve as bag sections, the face side of the bag being severed on the line 5, the pleats or tucks on the line 6 and the rear or seam side being severed on the line 7. The bottom of the bag is closed by bending one of the ends of the bag section on the line A—B and pasting this portion of

the bag, which forms a bottom flap 8, against a side of the bag. Heretofore, the back or seam side 2 of the bag has been made somewhat narrower than the opposite side or 5 face 1. But in folding the bottom flap of such a bag against the back or seam side thereof, the corners of the bottom flap projected beyond the longitudinal edges of the back or seam side of the bag, and, in consequence, 10 these corners of the bottom flap were left unpasted with respect to the body of the bag as there was no part of the back or seam side of the bag to receive these corners of the flap. As a result, bags made in that manner 15 were not leak-proof as powdery or granular material placed in such bags could escape through the unpasted corners of the bottom flap.

According to the present invention, the 20 back or seam side 2 of the bag, as will be seen from Figures 1 and 2, is wider than the opposite side or face 1. The bottom flap or fold 8, which is turned upwardly against and pasted to the back or seam side 2 of the 25 bag is narrower across its corners 8^a than the width of the back or seam side 2, and, hence, these corners of the bottom flap or fold, when folded against the back of the bag will be removed inwardly from the longitudinal 30 edges of the back of the bag and the latter will provide supports of ample area against which these corners of the bottom flap or fold may be pasted. By thus providing a support or backing of sufficient width at the 35 back of the bag to receive the corners of the bottom flap or fold, effective sealing and securing of these corners of the flap or fold are insured. The edges 6 of the pleats or tucks will lie beneath the bottom 40 fold 8 and will be pasted also to the back or rear face of the bag. As the corners 2^a of the tucks are produced by continuations of the longitudinal edges of the back or seam side 2 of the bag, these corners, 45 when folded and pasted against the back of the bag will be received within the width thereof, thus insuring ample backing or support against which these corners of the tucks will be pasted and thus sealed and secured. 50 Moreover, the ends of the tucks are overlapped by the outer portion of the bottom

fold, thus insuring protection against leakage at these points.

The right-hand lower corner of Figure 1 and Figure 3 illustrate clearly the manner 55 in which each corner 8^a of the bottom fold is received within the width of the back or seam side 2 of the bag. The full lines in each of these figures show the corner 8^a of the bottom fold turned back while the dotted 60 lines show this corner of the bottom flap received within the width of the back or seam side 2 of the bag and pasted thereto. These figures also show the corners 2^a received within the width of the back or rear side 2 65 and pasted thereto.

The paste to secure the bottom fold or flap may be applied either to the flap, to substantially cover it from the fold line A—B to its edge 5, or it may be applied to the back 2 70 of the bag above the fold line A—B to cover a sufficient area to insure pasting of all the edges of the flap and the tucks or pleats.

The present invention enables square-bottom bags of the type having pleats or tucks 75 in their edges to be produced which will be sift-proof, thus overcoming the objection previously existing in bags of this type, although the bags may be manufactured as expeditiously and inexpensively as heretofore. 80

I claim as my invention:

1. A square-bottom paper bag comprising a tube-like body having a pleat or tuck at each edge, and a bottom flap folded and pasted against a side of the body of the bag, 85 the side of the bag against which the bottom flap is pasted being wider than the opposite side of the bag and providing supports against which the corners of the bottom flap are pasted. 90

2. A square-bottom paper bag comprising a body having a longitudinal seam at one side and a pleat or tuck in each longitudinal edge thereof, and a bottom flap folded and pasted against the seam side of the bag, the 95 seam side of the bag being wider than the opposite side thereof and providing portions within its width to which the corners of the bottom flap are pasted.

In testimony whereof I have hereunto set my hand.

TRUE M. AVERY.
